Inventor

William A. Lorenz.

UNITED STATES PATENT OFFICE.

WILLIAM A. LORENZ, OF HARTFORD, CONNECTICUT, ASSIGNOR OF ONE-HALF TO HERMAN BEHR, OF BROOKLYN, NEW YORK.

SAND-PAPER.

SPECIFICATION forming part of Letters Patent No. 440,317, dated November 11, 1890.

Application filed March 19, 1888. Serial No. 267,619. (Specimens.)

To all whom it may concern:

Be it known that I, WILLIAM A. LORENZ, of Hartford, Connecticut, have invented a new and useful Improvement in Sand-Paper, 5 of which the following description and claim constitute the specification, and which is illustrated by the accompanying sheet of drawings.

This invention consists in a new and useful 10 kind of sand-paper.

Figure 1 of the drawings is a view of a piece 15 of my improved sand-paper with the sanded surface generally uppermost, but with the back of the sanded surface turned up to view at the right of the figure. Fig. 2 is an enlarged cross-section of a piece of sand-paper such as has generally been used. Fig. 3 is an enlarged cross-section of a piece of my improved sand-paper.

20 The letter A indicates a piece of my improved sand-paper finished, as shown in Fig. 1.

The letter B indicates the paper base of the sand-paper of Figs. 2 and 3, respectively, while the letter C indicates the glue, by means of 25 which the particles of sand are fastened to the paper base; and the letter D indicates the particles of sand themselves.

A suitable process of making my improved sand-paper consists in passing the sanded paper with the sanded side upward between two rollers, the upper one of which has a hard surface and the lower one of which has a sur-

face of soft vulcanized rubber or other elastic material, which yields to the downward pressure of the particles of sand which is exerted 35 through the paper base, so that those particles are embedded in the paper base and the paper base is pebbled thereby, substantially as shown in Fig. 3. The special merit of my improved sand-paper consists in several particulars. The particles of sand, being embedded in separate concavities in the upper surface of the paper base, are more firmly held in position against the friction which they must withstand in use than they can be 40 where they are not thus embedded; and my improved sand-paper of Fig. 3 can be manufactured with less glue than the sand-paper of Fig. 2, because the interstices between the various particles of sand are diminished in 45 size by the upward pressure of those portions of the surface of the lower roller that lie directly under those interstices.

I claim as my invention—

Sand-paper consisting of a base of pebbled 55 paper and of particles of sand embedded in the concavities in the upper surface of the pebbled base and united to the pebbled base by glue, all substantially as described.

WILLIAM A. LORENZ.
